OVEN FOR THE LOW TEMPERATURE DISTILLATION OF COAL, LIGNITE, OR THE LIKE

Filippo Tassara, Genoa, Italy

Application October 19, 1937, Serial No. 169,901
In Italy October 27, 1936

2 Claims. (Cl. 202—98)

The present invention relates to an oven for the low temperature distillation of coal, lignite, or the like.

According to the present invention, a distillation oven is heated with the products of combustion of a furnace, said oven being provided with one or more distillation retorts, the material to be distilled being charged in layers perpendicular, or substantially perpendicular to the axis of the retorts, each of said layers being separated by metallic movable diaphragms, the shape of which correspond to the internal shape of the retort, the column formed alternately by the layers and diaphragms being axially advanced in said retort, with continuous or intermittent movement, the material being rapidly and uniformly heated by the heating action performed by the metallic diaphragms.

According to the invention, the material to be distilled passes first through a pre-heating zone, maintained at a temperature of about 250-400° C. then through a distillation zone, maintained at a temperature of about 600° C. and eventually through a third cooling zone.

According to the invention a charging device for the material and for the metallic diaphragms is provided at the inlet of each of the retorts, while an exhaust and/or cooling device is provided at the discharge end of each retort.

The above mentioned metallic diaphragms, according to the invention, may be provided with parallel or otherwise suitably placed ribs, between which the material to be distilled is pressed by the action of increasing pressure in the retort and may thereby be shaped into blocks to facilitate the removal of the treated material.

These and other objects of the invention will clearly appear from the following description, with reference to the accompanying drawing which illustrates by way of example only a general plan of the oven, and one of its practical embodiments according to said invention.

Fig. 1 is a vertical cross section view illustrating diagrammatically a distillation oven according to the invention.

Fig. 2 is a perspective view of a metallic diaphragm supplied with ribs.

Fig. 3 is a vertical section according to the line III—III of Fig. 4 of a practical embodiment of an oven according to the invention.

Fig. 4 is a plan view of the oven seen in the direction of arrow IV of Fig. 3 and

Fig. 5 is, on the left side, an external view of the oven in the direction of the arrow V of Fig. 3

and on the right side a vertical section made according to the plane Va—Va of Fig. 3.

With reference to Fig. 1 the oven 1 is provided with a retort 2 that crosses it, said retort being heated either by the combustion gases of a furnace or by a battery of nozzles, which are indicated with dotted lines at 3. The retort inlet is provided with a charging device 4 constituted by a loading funnel 5, a feeding screw device 6 and an opening 7 for the introduction of iron plates 8 designed to form the separating diaphragms between the layers 9 of the material to be distilled.

The diaphragms are shaped so as to permit a good thermal conduction from the walls of the retort to them; and since the diaphragms are made of a good thermal conductor, they will uniformly distribute the heat to the interior of the mass constituting the layers 9.

The distillation occurs between the section A—A, in which the main heating of retort 2 begins and zone B—B from which the gases and distilled vapours escape through pipe 10. The discharge end of the retort 2 is provided with a fireclay door 11 that can be used when the distillation takes place with intermittent advancement of the material. The discharge end is also provided with an extending portion 2', closed by a door 12 which can be removed for the discharge of the diaphragms and provided with a discharging tube 13 for the distilled material. The tube 13 preferably opens into a box 14 filled with water up to the level 15, the end of said tube being immersed in the water.

The material, coal, lignite or the like, while in the oven is submitted to a gradual and uniform heating, due to the presence of the heat distributing diaphragms 8, while in the term of relatively thin layers 9. The axial pressure, applied to the column formed by the layers 9 and diaphragms 8 by the feeding screw device 6, or other suitable device causes its advancement towards the discharge end of retort 2, and the compression and agglomeration of the solid material after distillation, thus obtaining a coal of fine technical and commercial qualities.

According to the invention, the diaphragms 8, may be provided with parallel ribs 16, which are filled with the material to be distilled. This material turns plastic under the action of the heat and forms substantially rectangular blocks in the channels formed by the ribs 16 on the diaphragms.

With reference to Figures 3 to 5 which show a practical embodiment of the invention and in

which the several parts are indicated with the same references used for the analogous parts of Fig. 1, oven 1 is provided with several retorts in parallel relation. The retorts are heated by conduction through the cylindrical wall provided with fire clay lining 17 (Fig. 3) by the products of combustion of a furnace 3 or by similar gases obtained from a plant through ducts 18 and passages or nozzles 19 (Fig. 5). The charging inlet 10 of each retort is provided with a charging device 4 constituted by a loading funnel 5, a feeding screw device 6 which consists of a carriage 21 sliding at will on rails 22 and a motor 23 mounted on said carriage. The motor drives 15 through worm gears 24, a threaded shaft 25 supported by brackets 26 on which is mounted a threaded hub 28 (Fig. 4) axially movable in the direction of arrows 27. Two arms 29 are provided with a piston 30 which penetrates the opening 20 of retorts 2. In the example illustrated in Figs. 3 to 5, the opening 7 (of Fig. 1) for the introduction of diaphragms 8 has been eliminated. The diaphragms will instead be introduced successively step by step through the hole 20, while the material to be treated is introduced 25 between two successive diaphragms 9 step by step through funnel 5.

The heating gases coming either from the furnace 3 or from nozzles 19 are removed through 30 pipes 31 placed near the charging end of the retorts 2 so as to affect a counter-current of the heating gases and the material to be treated. In this manner, the layers of material to be treated are preheated at the discharge end of the retort 2 there is provided a cooling chamber 32.

The exhaust end of each retort 2 is provided 35 with a door 11, covered with fire clay material which may be removed from the exhaust end of the retort by any suitable means, for instance by a threaded shaft 33 supported and cooperating with brackets 34 and driven by a hand-wheel 35. Shaft 33 passes at 36 into an exhaust chamber 13, one of said chambers being provided for each retort 2. Each of the chambers 13 is provided with a water seal 37. The bottom of each 40 of the chambers 13 is provided with a fixed portion 38 and by a movable portion 39 hinged at 40; said movable portion may take the position 39' in order to discharge the material into the carriage 41 which travels on rails 42 so that all of 45 the retorts may be reached.

An exhaust pipe 10 for the gases and the distilled vapours is provided for each retort. The exhaust pipes 10 leading from several of the retorts are connected to a receiver 44 which contains water through which the distilled vapours 5 and gases bubble. The distilled vapours and gases are led from the receiver 44 through a pipe 45 to a single main receiver 46 which collects the gases and vapours of the whole plant.

The present invention has been described and 10 illustrated in a diagrammatical embodiment and also in a practical embodiment, but it will be understood that many variations can be made, especially with regard to the construction of the oven 1, the retorts 2, the feeding device 4 and 15 the discharging device 2' and 13 as well as the nozzles 19 and the exhaust means, the pressure means and the diaphragms interposed between two consecutive layers of material.

Having now particularly described and ascertained the nature of the present invention and in what manner the same is to be performed, I declare that what I claim is:

1. An oven structure for low temperature distillation of coal, lignite and similar materials 25 comprising at least one horizontal retort, in combination with a plurality of imperforate ribbed metal diaphragms corresponding in shape to the cross-section of the retort, said retort being provided with means for the insertion of said diaphragms at the charging end, means for charging the material to be treated into the retort between the diaphragms to form relatively thin layers of said material, means for heating the retort, means for applying pressure to the diaphragms and the material therebetween from the charging end to compress the material, said diaphragms conducting heat to each layer of material whereby each layer is heated substantially uniformly throughout, means for removing gases 40 from the retort and means for releasing pressure at the discharge end to effect removal of the diaphragms and compressed material from the retort by said pressure means.

2. A device as claimed in claim 1, wherein the 45 means for charging the material into the retort operates intermittently.
